UNITED STATES PATENT OFFICE.

MAURICE B. LONG, OF EAST ORANGE, NEW JERSEY, ASSIGNOR TO WESTERN ELECTRIC COMPANY, INCORPORATED, OF NEW YORK, N. Y., A CORPORATION OF NEW YORK.

SELECTIVE CIRCUITS.

Application filed June 17, 1922. Serial No. 568,945.

To all whom it may concern:

Be it known that I, MAURICE B. LONG, a citizen of the United States of America, residing at East Orange, in the county of Essex and State of New Jersey, have invented certain new and useful Improvements in Selective Circuits, of which the following is a full, clear, concise, and exact description.

This invention relates to improvements 10 for selectively receiving and transmitting alternating currents.

In a copending application of Paul H. Pierce, Serial No. 484,342, filed July 13, 1921, assigned to the assignee of this application, there is described a method of and means for selectively receiving alternating currents of which this invention is an improvement.

An object of the present invention is to 20 maintain high selectivity in a tuned circuit associated with a translating device. In a multiplex signaling system it is desirable to maintain a high degree of selectivity in the tuned circuits which separate the several 25 transmissions and which are located between the transmission line and the terminal translating devices, in order to provide as many transmission channels as possible within a given frequency range. A second object of 30 this invention is to provide highly selective circuits for such a system. Other objects will become apparent from the description to follow.

According to this invention a loop tuned 35 circuit is associated with a translating device by means of an energy modifying or transforming means. In one embodiment of the invention this means comprises a step-down transformer having its high impedance 40 winding connected to the tuned loop and its low impedance winding, to the translating device. In a more specific embodiment of the invention the receiving circuit for a multiplex carrier current telegraph system comprises a loop tuned circuit supplying energy 45 to the input circuit of a thermionic vacuum tube amplifier through an inequality impedance ratio step-down transformer. The input impedance of the amplifier, when viewed 50 from the high impedance winding of the transformer, appears larger than is actually the case. Since it is this winding, which is connected in shunt to a portion of the tuned loop, less energy loss is caused by this ar-

angement than if the amplifier itself were 55 directly connected to the tuned loop.

This invention also contemplates the use of other energy changing or transforming devices equivalent to the step-down transformer. It also contemplates the substitution of other translating devices, such as electron-discharge detectors, rectifiers of various kinds and like devices.

The invention will now be further described with reference to the drawing in 65 which Fig. 1 shows one embodiment thereof in a carrier wave signaling system; Figs. 2 and 3 show graphically the results of tests which are evidence of the improvement provided by this invention; and Fig. 4 is a modified circuit arrangement showing the invention embodied in a transmitting circuit.

Referring now to Fig. 1, the carrier wave signaling system, therein shown, comprises a transmission line ML to which a plurality 75 of transmitting stations are connected through the balanced transformer 5 with its associated balancing network NW and to which a plurality of cooperating receiving stations are connected through the balanced 80 transformer 6 with its associated network NE. Each transmitting station comprises an oscillator O, an amplifier TA and a loop tuned circuit LW comprising a lumped inductance 7, the primary winding of transformer 9 and a condenser 8. This loop tuned circuit LW is loosely coupled through transformer 9 to a series tuned circuit comprising a capacity element 10 and the inductive coils 11, 11 constituting the secondary 90 winding of the transformer 9. This series tuned circuit in turn is connected through the common transmitting circuit TCW to the balanced transformer 5. The oscillator O is normally active but for signaling purposes oscillations are prevented from being transmitted to the common line ML by a short circuit for the oscillations at the amplifier TA. This short circuit is controlled by the key K in series with a large capacity 95 which is of negligible impedance for the oscillations produced by source O.

The oscillator O may be of any suitable type, preferably an electron discharge oscillator such as is described in Hartley Patent No. 1,356,763, October 26, 1920. Likewise, the amplifier TA comprises preferably an electron discharge device in general like the

high frequency amplifiers HFA¹ and HFA², hereinafter to be described more in detail, but it may be of any other suitable type

5 Each of the plurality of transmitting channels is similarly arranged and connected with the common line ML through the transformer 5 and common transmitting circuit TCW.

10 Each receiving circuit comprises a series tuned circuit having capacity element 12 and inductive elements 13, 13, connected to the common line ML through the common receiving circuit RCE and the balanced transformer 6. Loosely coupled to this series 15 circuit, through the transformer 14, is a loop tuned circuit comprising the secondary winding of transformer 14, an inductive element 15 and a capacity element 16. Connected to this loop tuned circuit, through a step-down 20 transformer 17, is a high frequency amplifier HFA¹ connected through a potentiometer 18 to a second high frequency amplifier HFA², which in turn is directly connected to a detector D. Receiving device 19, responsive to 25 unidirectional current from the detector D is connected thereto.

30 The high frequency amplifiers HFA¹ and HFA² and the detector D are preferably of the well known three element electric discharge type. The amplifier HFA¹ has a filament 20, a grid 21 and a plate 22. The amplifier HFA² has a filament 23, a grid 24 and a plate 25. The detector D has a filament 26, a grid 27 and a plate 28. The three filaments 20, 23 and 26 are connected serially 35 with a battery 29 and a resistance 30. The function of this resistance is to normally maintain the grid 21 at a small negative potential with respect to the filament 20. Between the filament and the plate of each device is a battery 31. Between the battery 31 and the plate 22 of high frequency amplifier HFA¹ and the plate 25 of the high frequency amplifier HFA² are connected respectively choke coils 32 and 33. The function 40 of these coils is to permit the flow of direct current while substantially preventing the flow of any alternating current. Receiving device 19 is connected in series with the battery 31 between the plate 28 of the detector D and the series filament circuit. A condenser 34 is connected in shunt of the receiver 45 19 to improve the operation of the detector D in a manner which is well known. The stopping condensers 35 and 36 are provided to prevent the flow of direct current 50 from the battery 31 to the potentiometer 18 and the resistance 38 associated respectively with the high frequency amplifier HFA² and the detector D. Between the series filament circuit and the grid 27 of detector D is connected a battery 37 and the high resistance 55 38. The battery 37 has its negative terminal connected to the grid 27 through the high resistance 38, which with condenser 36 acts as

a grid leak, the operation of which in connection with a detector is well known and therefore needs no further description.

60 The high impedance winding 40 of transformer 17 is connected to the terminals of 70 condenser 16 in the loop tuned circuit LE. The low impedance winding 41 of the transformer 17 is connected to the input of the high frequency amplifier HFA¹. Due to this arrangement the input impedance of the 75 high frequency amplifier HFA¹, appears much larger than it actually is, when viewed from the terminals 42, 43 of the high impedance winding, which terminals are connected to the loop tuned circuit LE. The sharpness 80 of tuning of the loop LE is therefore little affected by the other apparatus in the receiving circuit.

85 Each of the plurality of receiving channels is similarly arranged and connected to the common line ML through the transformer 6 and the common receiving circuit RCE.

90 It is understood that a distinctive carrier frequency is employed for each transmitting channel and its cooperating receiving channel and that the constants of the tuned circuits of the several channels will necessarily be different in order that each of the different carrier frequencies may be confined to 95 its proper channel. It is also to be understood that a plurality of receiving channels may be connected to the balanced transformer 5 by means of a common receiving circuit RCW and that a plurality of transmitting circuits may be connected to the balanced transformer 6 by means of the common transmitting circuit TCE. For simplicity, such channels are not shown in the arrangement of Fig. 1.

100 105 Referring now to Figs. 2 and 3, Fig. 3 shows the selectivity of the receiving circuit of Fig. 1 for various frequency spacings and signal frequencies. Fig. 2 shows the same data with respect to a circuit such as disclosed in the above mentioned copending Pierce application.

110 The abscissae in each figure represent the frequency spacing between channels in cycles per second. The ordinates in each case are 115 numbers which are a measure of the selectivity of the individual circuit. The numbers opposite the several curves show the frequency to which the receiving circuit was tuned when the data for that curve was 120 obtained. For example, assume that the receiving circuit LE shown in Fig. 1 is tuned for 7000 cycles per second. Other similar receiving channels are tuned for frequencies on either side at intervals of 400 125 cycles. At the transmitting station are sources arranged to supply currents of these frequencies to the common line ML. Under these circumstances the selectivity shown by the intersection of the curve labeled 7000 130

with the ordinate marked 400 is slightly over 20, which means that the effect of the detector D associated with circuit LE of current of 7000 cycles is approximately 5 twenty times as great as the maximum effect of any one of the other frequencies. For the same frequency spacing of 400 cycles and signal frequency of 7000 cycles, the selectivity shown by Fig. 2 at the intersection of the curve labeled 7000 with the ordinate marked 400 is about 16, or about twenty per cent less. Or, in order to obtain a selectivity of 20, a frequency spacing of about 10 450 cycles would be required in the Pierce 15 system.

From these results it is seen that the receiving circuit of this invention provides a decided improvement as to selectivity for a given frequency spacing or frequency spacing 20 for a given selectivity over previously known receiving circuits. This improvement in selectivity or reduction in frequency spacing is obtained moreover with only a negligible sacrifice in efficiency. It may also 25 be noted in this connection that in actual commercial practice the use of the circuit of this invention has made it possible to obtain ten duplex telegraph transmission channels within the frequency range required 30 previously for eight such channels.

In the commercial system just referred to the transformer 14 has 660 turns in the high impedance winding 13, 13, and 17 turns in the low impedance windings or an impedance 35 ratio of approximately 1500 to 1. Inductive element 15 consists of a double winding toroidal coil having a total of 660 turns. The inductance of this coil at 1000 cycles per second is 150 millihenrys and at 7000 40 cycles per second 160 millihenrys. The capacity of the condenser 16 is adjusted to approximately .00323 microfarads for the 7000 cycle channel in order to make the circuit resonant at that frequency. High 45 impedance winding 40 of transformer 17 consists of 5500 turns and the low impedance winding 41 of 1900 turns giving an impedance ratio of 8.5 to 1.

In the modification of Fig. 4 the invention 50 is applied to a transmitting circuit which may be substituted for the transmitting circuit of Fig. 1 if desired. Like reference characters are used to designate like elements in both Figs. 1 and 4.

The oscillator O supplies energy to the 55 loop tuned circuit LW through the electron discharge amplifier TA¹ and the inequality impedance ratio transformer 50. The low 60 impedance winding 53 is connected to the output circuit of the amplifier TA¹ and the high impedance winding 54, to the loop tuned circuit LW at the points 51, 52. The relatively low impedance of the output circuit of the amplifier TA¹ therefore appears 65 as a relatively higher impedance when

viewed from the points 51, 52 of the loop tuned circuit LW. As previously explained in connection with the receiving circuit of Fig. 1 such a connection maintains the selectivity of the loop tuned circuit. 70

Although this invention has been specifically described as embodied in a carrier wave signaling system, it is to be understood that it is applicable to selective circuits generally without regard to the purpose for which they are used. The invention is therefore to be limited only by the scope of the appended claims. 75

What is claimed is:

1. A current wave transmission system 80 comprising a loop tuned circuit, a translating device, and a step-down transformer connected between said loop tuned circuit and said translating device for the transfer of energy therebetween. 85

2. A current wave receiving system comprising a loop tuned circuit, a detecting device receiving energy from said loop, and a step-down transformer connected between 90 said loop tuned circuit and said detecting device.

3. A selective electric wave transmission system comprising a loop tuned circuit, a translating device, and an impedance changing device so connected between said tuned 95 circuit and said translating device that the impedance of the latter as measured from the point of connection to the former is increased.

4. In an electric wave receiving system, an inductive element and a capacitative element connected in parallel with each other to form a tuned circuit, a detecting device, and an inequality impedance ratio transformer having the terminals of its high impedance winding connected to electrically separated points of said tuned circuit and the terminals of its low impedance winding connected to said detecting device. 100

5. A multiplex signaling system comprising 105 a plurality of different frequency wave transmitting circuits, a plurality of cooperating receiving circuits, a common transmission medium uniting said transmitting and receiving circuits by means of which the different frequency waves are conveyed 110 from the transmitting circuits to the receiving circuits, and a loop tuned circuit, a step-down transformer and an electron discharge device connected in series with each 115 of said receiving circuits.

6. In a multiplex signaling system, a common transmission circuit, a plurality of receiving circuits connected thereto each primarily responsive to a frequency different from the others, each said receiving circuit comprising a loop tuned circuit, a step-down transformer having its high potential terminals connected to said loop tuned circuit, and a translating device having its 120 125 130

- input circuit connected to the low potential terminals of said step-down transformer.
7. In a multiplex signaling system a common transmission circuit, a plurality of receiving circuits connected thereto each primarily responsive to a frequency different from the others, each said receiving circuit comprising a loop tuned circuit, a step-down transformer having its high potential terminals connected to said loop tuned circuit, and an electron discharge amplifier having its input circuit connected to the low potential terminals of said step-down transformer.
8. A selective alternating current receiving circuit comprising an inductive coil and a condenser connected in parallel, a step-down transformer having its high potential terminals connected to the terminals of said condenser, and an electron discharge device having an input and an output circuit, said input circuit being connected to the low potential terminals of said step-down transformer and the output circuit associated with a signal receiving device. 15
